ELECTROLYTIC CONDENSER

Paul McKnight Deeley, New York, N. Y., assignor
to Cornell-Dubilier Corporation, New York,
N. Y., a corporation of New York

Application June 24, 1935, Serial No. 28,033

12 Claims. (Cl. 175—315)

This invention relates to electrolytic condensers and methods of making such condensers, more particularly to condensers of the so-called "wet" or aqueous type in which an electrode having a dielectric film formed thereon by electro-chemical treatment is mounted within a metal container or casing containing a liquid electrolyte.

The primary object of the invention is to provide an improved construction of condensers of this type, in particular an improved construction of the formed electrode or anodic member which can be economically manufactured and is efficient in operation as compared to similar devices hitherto known in the art.

According to a commonly used construction of wet electrolytic condensers, the anode is comprised of a metal sheet wound into a cylindrical spiral and mounted coaxially within a cylindrical metal container. This and similar constructions known in the art possess the disadvantage that the electric current passing through the electrolyte has to travel from the inner center of the electrode all the way along its axial path to the outside container usually forming the negative terminal of the condenser. This long average current path through the electrolyte causes high internal resistance losses and a high power factor of the condenser.

It is an object of this invention to provide a construction of the anode or formed electrode member for wet electrolytic condensers insuring a minimum average current path between the anode member and the negative electrode, such as the metallic container of the condenser.

Another object of the invention is the provision of an anodic member adapted for use in wet electrolytic condensers which may be subjected to efficient preparatory treatment, such as mechanical roughening or chemical etching for increasing the effective anode surface and accordingly the electrical capacity of the condenser.

Another object of the invention is the provision of a rigid anodic member of novel construction adapted for use in wet electrolytic condensers by which corrosion effects due to contact of adjacent portions of the anode surface is substantially prevented.

Further objects and novel aspects will appear hereinafter from the detailed description as follows taken with reference to the accompanying drawing in which:

Fig. 1 is a sectional side elevation of one construction of condenser according to the invention, and

Fig. 2 is a cross-sectional view on a larger scale taken on line 2—2 Fig. 1.

Similar reference numerals identify similar parts in both views.

In the improved condenser according to this invention, the anode consists of a flat electrode such as a metallic sheet or ribbon edgewise wound into a helix and having its ends suitably supported such as by means of a carrier and/or electrode member which passes through one end of the container and is suitably insulated therefrom. The thus obtained helicoidal electrode, while insuring a maximum effective condenser surface and maximum capacity for a condenser structure of given size and bulk, presents the further advantage of minimum length of the current path from the anode surface to the cathode or metal container thus insuring a minimum internal resistance and loss in the condenser. Preferably the carrier member for supporting the helicoidal electrode passes through a plug of a flexible insulating material such as rubber which is held in position by pressing portions of the end of the container against it so that the plug is deformed and a liquid-tight seal obtained.

Referring to the drawing, the condenser shown comprises a metallic container 1 preferably of cylindrical shape and consisting of suitable metal, such as aluminum or the like. This container is preferably made in a single unit such as by a pressing or drawing process from a thin aluminum tube. The container has an enlarged, preferably screw-threaded neck portion shown at 4 for mounting the condenser on the support or platform in inverted position in accordance with the usual practice and as indicated in the drawing. The anodic member or formed electrode shown at 3 consists of a metallic ribbon of suitable film forming material preferably high purity aluminum being wound edge-wise into a helix to form a helicoidal surface and having its opposite ends connected to a suitable support such as a riser rod or carrier member shown at 2 disposed along the cylindrical axis of the container 1. The connection of the anode 3 and the carrier member 2 may be carried out in any well known manner such as by means of rivets shown at 6 and 7. The rivets 6 and 7 should be of the same material as the anode riser rod 2, namely of film forming metal, for example, high purity aluminum. The rod 2 should also be of film forming metal such as aluminum in the example described as it too is a part of the anode member. In this manner, corrosion effects at the joints are prevented. The carrier member 2 is passed through a resilient

plug 3 of relatively flexible insulating material preferably consisting of rubber and placed within the extending neck portion 4 of the container. The upper unthreaded part of the neck 4 is deformed such as by pressing a suitable tool against the neck in order to secure a liquid-tight and firm joint between the container, the rubber plug 3 and the carrier member 2. The anode carrier or riser rod 2 has preferably a round cross-section as shown to present a smooth surface with no sharp edges or corners and to secure a tight seal throughout the rubber insulating brushing or plug 3. Thus when the metal neck is swaged or crimped the plug will tighten around the riser rod

15 with equal pressure in all directions, thus affording an efficient liquid tight seal. The round rod is suitably swaged or flattened at the points where the helical anode strip is riveted in place. The upper end of the carrier member 2 projecting

20 through the plug 3 constitutes the terminal of the electrode and may be provided with a suitable connecting means, such as a clamping nut, soldering lug, etc., for connecting the condenser in an electrical circuit.

25 In the manufacture, the edge-wise wound ribbon 3 is first suitably treated and formed with an anodic film and then riveted onto the carrier member 2 as shown in the drawing. The plug 3 is then placed in position and the whole assembly

30 mounted in the container 1 in a manner as described before. The container is then inverted and filled with sufficient electrolyte to cover the electrode but to leave space above the electrolyte level. The cover 10 is then placed over the open

35 end and spun on so as to seal this end in a liquid-tight manner. If desired, a washer 11 may be included in the joint between the container 1 and the cover 10 so as to insure that this joint is liquid-proof. This washer may consist of rubber, var-

40 nishes, cambric or a piece of gauze impregnated with a wax compound. In the latter case, the operation of spinning over the edge of the cover will produce sufficient heat to melt the wax so that when it cools it will seal the joint. If dur-

45 ing operation excess heat is generated in the condenser the wax will melt or soften sufficiently to relieve any excess gas pressure and when the condenser cools the wax will harden again to re-seal the joint. The space above the electrolyte serves

50 to receive any gases evolved during the operation of the condenser. If desired, an additional vent may be provided for the escape of these gases although usually this is not required.

To prevent the anode from coming in accidental contact with the walls of the container, a spacing element of suitable insulating material which is not attacked by the electrolyte, such as a spacer 9 of hard rubber or celluloid and the like is arranged between the anode 3 and the walls

60 of the container. To insure free access of the electrolyte to both the container and the anode surface, spacer 9 is provided with perforations of suitable size and spacing as shown in the drawing.

If the anode 3 is subjected to a preparatory roughening or chemical etching process prior to the film forming operation, such treatment should be carried out prior to the mounting or riveting of the electrode to the carrier member 2 in order to prevent corrosion at the connecting joints and insure a tight mechanical joint.

65 As is obvious, the screw-like shape of the anode surface as described insures a minimum average length of the current path between the anode and the cathode members, resulting in a minimum of internal resistance and heat losses in the con-

70 denser. In addition, the anode may have a sufficient thickness to allow of a sufficiently deep and efficient etching or similar surface treatment such as mechanical roughening (sand-blasting or the like) preparatory to the forming of the dielectric film thereon in such a manner as to insure a maximum capacity of the condenser and a dielectric film of high electrical and mechanical properties. In addition, this construction presents a semi-rigid structure practically eliminating the possibility of accidental contacts of adjacent portions of the anode surface and resultant undesirable corrosion effects during the use of the condenser. Furthermore, the construction of the invention is simple and economical in manufacture 15 as compared with known methods and designs requiring elaborate and expensive machinery and manufacturing processes.

75 While I have described my invention with reference to the specific embodiment as illustrated in the drawing, I do not wish to be limited to the details thereof except as set forth in the appended claims.

I claim:

1. An electrolytic condenser having a metallic 25 container, an electrolyte and a film forming electrode within said container, said electrode consisting of an edge-wise wound flat metallic ribbon helix, and a support for said electrode comprising a rod freely passing through the windings of said 30 helix, the opposite ends of said helix being rigidly connected to said rod.

2. An electrolytic condenser having a metallic container, an electrolyte therein, a carrier member passing through one end of said container, 35 and a film forming electrode consisting of an edge-wise wound ribbon helix concentrically and freely surrounding said carrier member and having its opposite ends supported by said carrier member.

3. An electrolytic condenser having a cylindrical metallic container, an electrolyte therein, a carrier member disposed coaxially within said container and passing through one end of said container and being insulated therefrom, and a 45 film forming helicoidally wound flat ribbon electrode freely surrounding said carrier member and having its opposite ends supported by said carrier member.

4. An electrolytic condenser having a cylindrical metallic container, an electrolyte therein, a carrier member disposed coaxially within said container and passing through one end of said container and being insulated therefrom, and a film forming helicoidally wound flat ribbon electrode concentrically and freely surrounding said carrier member and having its opposite ends rigidly connected to said carrier member.

5. An electrolytic condenser having a metallic 60 container, an electrolyte therein, a film forming electrode immersed in said electrolyte consisting of a flat edgewise wound metallic ribbon helix, and a rigid carrier rod passing through an insulating bushing in a wall of said container and supporting the opposite ends of said helix.

6. An electrolytic condenser having a cylindrical metallic container, an electrolyte therein, a carrier member disposed along the axis of said container and a film forming electrode consisting of a flat metallic ribbon wound into a helicoidal 70 member, said electrode concentrically and freely surrounding said carrier member and having its opposite ends rigidly connected to said carrier member.

7. An electrolytic condenser having a metallic 75

5 container, an electrolyte therein, a film forming electrode immersed in said electrolyte consisting of an edge-wise wound metallic ribbon helix, and a rigid carrier member passing through and supported by a liquid-tight insulating bushing in a wall of said container and supporting the opposite ends of said helix.

10 8. An electrolytic condenser having a metallic container, an electrolyte therein, and a film-forming electrode immersed in the electrolyte, comprising a carrier member disposed along the axis of said container and an edge-wise wound metallic ribbon helix concentrically and freely surrounding said carrier member and having its opposite ends rigidly connected to said carrier member.

15 9. An electrolytic condenser having a cathode container, an electrolyte therein, a film-forming electrode immersed in the electrolyte, comprising 20 a carrier member disposed along the axis of said container and an edge-wise wound metallic ribbon helix concentrically and freely surrounding said carrier member and having its opposite ends rigidly connected to said carrier member, and a liquid-tight insulating bushing in a wall of said container, said carrier member being passed 25

through and projecting outwardly from said bushing.

10 10. An electrolytic condenser having a cathode container, an electrolyte therein, and a film-forming electrode immersed in the electrolyte 5 comprising a metal rod disposed along the axis of said container and an edge-wise wound flat ribbon helix of film-forming metal substantially the same as said rod, said helix freely surrounding said rod, said rod having flattened portions 10 adjacent and connected to the opposite ends of said helix.

11. In an electrolytic condenser as claimed in claim 10, including an insulating bushing in a wall of the container, said rod being passed 15 through and supported by said bushing to serve as a terminal for said electrode.

12. In an electrolytic condenser in combination with a cathode container and an electrolyte therein, an anode comprising a rod supported in 20 an upright position and centrally located relative to the container, and a continuous strip of sheet-like metal being edge-wise wound about said rod and having its opposite ends rigidly connected to said rod. 25

PAUL McKNIGHT DEELEY.
